PRESSURE ACTUATED SWITCH

Jacob L. Pauly, Hasbrouck Heights, N. J., assignor
to Bendix Aviation Corporation, Teterboro,
N. J., a corporation of Delaware

Application December 2, 1948, Serial No. 63,060

3 Claims. (Cl. 200—83)

1

The present invention relates to electrical circuit makers, and more particularly to a pressure actuated switch adapted for use with oxygen demand regulators.

An object of my present invention is to provide a sensitive pressure actuated switch operable on pressures between 6 inches of water pressure and 25 pounds per square inch encountered in oxygen demand regulators.

A further object of my invention is to provide a pressure actuated switch of the character indicated in which the pressure of the fluid acts against a diaphragm and calibrated spring, and in which no back pressure is built up by the movement of the diaphragm.

Another object of this invention is to provide a pressure actuated switch of the character indicated in which the friction of moving parts is reduced to a minimum due to the large bearing surfaces provided therein.

Still another object of my invention is to provide a pressure actuated switch of the character indicated in which the diaphragm acted upon by the fluid pressure in turn acts upon a piston surface having approximately the same area as the diaphragm to insure positive action of the switch in response to fluid pressures.

Still a further object of the invention is to provide a pressure actuated switch of the character described in which the response of the switch to operating pressures may be varied.

Yet another object of my invention is to provide a pressure actuated switch which shall consist of few and simple parts, relatively inexpensive to manufacture, automatic and positive in its operation, which shall have a large variety of application and yet be practical and efficient to a high degree in use.

Other objects of the invention will in part be obvious, and in part hereinafter pointed out.

The invention accordingly consists in the features of construction, combinations of elements and arrangement of parts which will be exemplified in the construction hereinafter described and of which the scope of application will be indicated in the appended claims.

In the accompanying drawing forming a part of this specification in which one of the various illustrative embodiments of my invention is shown as a longitudinal cross-sectional view with portions shown in elevation, the numeral 10 designates a pressure actuated switch enclosed in a housing 11 which is fixed to a mounting flange 12 as by screws 13.

The mounting flange 12 is provided with a

2

threaded stud 14 and formed with an opening or port 15 through which the fluid pressure is introduced into the housing 11. The housing 11 is provided with an integral flange 16 at the base thereof, said flange being formed with dependent annular member 17. In fastening the housing 11 to the mounting flange 12 the dependent member 17 forms a chamber 20 between the flange and the housing. A resilient diaphragm 21 is fastened between the mounting flange 12 and the dependent member 17 by the screws 13, the diaphragm 21 being thus adapted to be expanded to the dotted line position shown upon an increase in pressure through the port 15.

Fixed within the housing 11 and longitudinally disposed therein is a sleeve 25 formed with elongated slots 26, for the purposes hereinafter appearing. The upper end of the sleeve 25 is provided with a threaded portion 28, an adjustment nut 29 being threaded thereon.

Slidably received within the sleeve 25 is a piston 30, the upper end 31 of the piston extending slightly above the upper end of the sleeve 25. Fixed to the lower end of the piston 30 as by screw 33 is a rigid abutment plate 35, said abutment plate being within the diaphragm chamber 20. Fixed to the upper end 31 of the piston is an abutment pin 38. The movement of the piston 30 within the sleeve 25 is limited by a pin 40 passing through said piston and registering in the slots 26 of the sleeve. Two spring retainers 41 and 42 are provided about the sleeve 25, the one abutting the nut 29, the other abutting the pin 40. A coil compression spring 43 wound about the sleeve 25 and interposed between the two retainers 41 and 42 tends to urge the piston 30 and its abutment plate 35 in a downward direction against the diaphragm 21.

The increasing pressure acting upon the diaphragm 21 through the port 15 will tend to raise the diaphragm 21. The diaphragm will press against the abutment plate 35 to move the piston 31 against the action of the spring 43. It will be appreciated that the area of the abutment plate 35 is approximately that of the diaphragm 21 so that any pressure of the fluid acting upon the diaphragm is transmitted directly to the piston 30.

The movement of the abutment plate 35 within the chamber 20 will compress any air entrapped above the abutment plate 35. The compression of this entrapped air would tend to offer a greater resistance to the movement of the piston

30. To offset the cushioning effect of the entrapped, air ports 45 are provided in the bottom wall of the housing 11 interconnecting the chamber 20 with the interior of the housing. Any air now that is behind the abutment plate 35 will be forced through the ports 45 into the interior of the casing 11, the larger volume of the casing 11 preventing any cushioning effect as previously described.

Fixed across the top of the housing 11 as by screws 48 is a mounting plate 49. Fixed to the underside of the plate 49 is a contact assembly 50 comprising an insulating plate 51, a stationary contact 52 and a U-shaped leaf spring 53 carrying at its free end a contact 54. An electrical coupling 56 is mounted to the top of plate 49 for connecting the contacts 52 and 54 to an external electrical circuit (not shown) whereby a signal or alarm may be given upon engagement of the two contacts.

The upward movement of the piston 30 due to the expansion of the diaphragm 21 will carry the abutment pin 38 upwardly to engage the outer end of the leaf spring 53. The leaf spring will be compressed so that the moveable contact 54 will be brought into engagement with the fixed contact 52. A fall in pressure within the chamber 20 will permit the spring 43 to return the piston 30 to its neutral or normal position permitting the contacts 52 and 54 to disengage thereby breaking the electrical circuit.

It will be apparent that the position of the nut 29 on the sleeve 25 will determine the bias of the spring 42. Thus the pressure at which the contacts 52 and 54 will engage can be regulated by screwing the nut 29 into various positions along the sleeve.

It will thus be seen that there is provided a pressure actuated switch in which the several objects of this invention are achieved and which is well adapted to meet the conditions of practical use.

Having thus described my invention, I claim as new and desire to secure by Letters Patent:

1. A pressure actuated switch comprising a housing, a mounting for said housing, said housing and said mounting forming a chamber therebetween, a diaphragm within said chamber, a port in said mounting adapted to be connected to a fluid pressure source and registering with said chamber, a sleeve longitudinally disposed in said housing and provided with elongated slots therein, a piston within said sleeve, abutment means fixed to said piston and protruding through said slots, means adjustably fixed externally to said sleeve in spaced relation to said slots, a plate disposed in said chamber adjacent said diaphragm and affixed to one end of said piston, biasing means interposed between said abutment means and said adjustable means and disposed externally of said sleeve for biasing said plate into engagement with said diaphragm, and a

switch adapted to be actuated by the other end of said piston upon movement thereof by said diaphragm.

5 2. A pressure actuated switch comprising a housing, a mounting for said housing, said housing and said mounting forming a chamber therebetween, a diaphragm within said chamber, a port in said mounting adapted to be connected to a fluid pressure source and registering with said chamber, a sleeve longitudinally disposed in said housing and provided with elongated slots therein, means adjustably fixed externally to said sleeve adjacent one end thereof, a piston within said sleeve, a pin affixed to said piston and protruding through said slots, a plate disposed in said chamber adjacent said diaphragm and affixed to the one end of said piston remote from said one end of said sleeve, means externally of said sleeve interposed between said 15 pin and said adjustable means for biasing said plate into engagement with said diaphragm, and a switch adapted to be actuated by the other end of said piston upon movement thereof by said diaphragm.

20 3. A pressure actuated switch comprising a housing having a chamber formed therein, a mounting secured to said housing so as to form a second chamber therebetween, a diaphragm secured between said housing and said mounting 25 within said second chamber, a port in said mounting adapted to be connected to a fluid pressure source and registering with said second chamber, a sleeve longitudinally disposed in said housing, a piston within said sleeve, a plate secured to said piston movable therewith within said second chamber and adapted to be engaged by said diaphragm, a plurality of cushioning eliminating ports interconnecting the two mentioned chambers so that actuation of said plate by said diaphragm provides negligible resistance to the 30 displacement of said plate, and a switch adapted to be actuated by the other end of said piston upon movement thereof by said diaphragm.
